Specification for Design.

Patented Sept. 20, 1921.

Application filed March 18, 1921. Serial No. 453,397. Term of patent 3½ years.

To all whom it may concern:

Be it known that I, ROLAND S. TROGNER, a citizen of the United States, residing at Akron, in the county of Summit and State of Ohio, have invented a new, original, and ornamental Design for a Tire, of which the following is a specification, reference being had to the accompanying drawing, forming a part thereof.

Figure 1 is a transverse sectional view shown in perspective, of a portion of the tire casing; and

Fig. 2 is a top plan view of a portion of the tire casing.

I claim:

The ornamental design for a tire as shown.

ROLAND S. TROGNER.
